United States Patent Office

Des. 215,418
Patented Sept. 30, 1969

215,418

BUILDING STRUCTURE

Richard P. Anderson, White Bear Lake, Minn.
(1732 Lawrence St., Cottage Grove, Minn. 55016)

Filed Oct. 16, 1967, Ser. No. 9,006

Term of patent 14 years

Int. Cl. D25—04

U.S. Cl. D13—1

FIG. 1 is a perspective view of a design for a building structure embodying the concepts of my invention;

FIG. 2 is a side elevation view of the building structure; and

FIG. 3 is a front elevation view of the building structure.

I claim:

The ornamental design for a building structure, as shown and described.
